US00D718458S

(12) **United States Design Patent**
Vosch et al.

(10) **Patent No.:** US D718,458 S
(45) **Date of Patent:** ** Nov. 25, 2014

(54) **ELECTRODE PATCH ARRAY**

(71) Applicant: **Tesseract Sensors, LLC**, Sanford, FL (US)
(72) Inventors: **Michael J. Vosch**, Titusville, FL (US); **Benjamin M. Downey**, Sanford, FL (US)

(73) Assignee: **Tesseract Sensors, LLC**, Sanford, FL (US)

(**) Term: **14 Years**

(21) Appl. No.: **29/480,616**

(22) Filed: **Jan. 28, 2014**

(51) **LOC (10) Cl.** 24-01

(52) **U.S. Cl.**

USPC **D24/187**

(58) **Field of Classification Search**

USPC D24/168, 186-187, 200, 232; 600/372-384, 390-393, 509; 607/62, 607/121, 148

(57) **CLAIM**

We claim the ornamental design for the electrode patch array, as shown and described.

DESCRIPTION

FIG. 1 is a top perspective view of an electrode patch array showing our new design;

FIG. 2 is a bottom perspective view thereof;

FIG. 3 is a top view thereof;

FIG. 4 is a bottom view thereof;

FIG. 5 is a side view thereof;

FIG. 6 is a side view that opposed the side view of FIG. 5 thereof;

FIG. 7 is a front view thereof; and,

FIG. 8 is a back view thereof.

1 Claim, 4 Drawing Sheets
